UNITED STATES PATENT OFFICE.

JOHN F. SCHEIDT, OF WIMBLEDON, NORTH DAKOTA.

CLOTHES-DRIER.

1,232,982.

Specification of Letters Patent. Patented July 10, 1917.

Application filed June 6, 1916. Serial No. 101,974.

To all whom it may concern:

Be it known that I, JOHN F. SCHEIDT, a citizen of the United States, residing at Wimbledon, in the county of Barnes and 5 State of North Dakota, have invented new and useful Improvements in Clothes-Driers, of which the following is a specification.

This invention relates to improvements in clothes driers and more particularly to 10 that class thereunder known as adjustable clothes driers.

The primary object of the invention is the provision of a device of the above stated character wherein improved means are employed for effecting the vertical adjustment of the supporting member, whereby the clothes to be dried may be easily and quickly placed upon the drier and the drying of the same will be more readily accomplished.

A further object of the invention is the provision of a cap having a plurality of sockets for detachably receiving hanger arms and guides arranged on the hanger 25 arms in which the clothes lines are arranged.

Figure 1 is a perspective view of the drier;

Fig. 2 is a vertical section taken through 30 Fig. 1;

Fig. 3 is a detail transverse sectional view illustrating the manner of connection of the base portion of the elevating means with the ridge post; and

Fig. 4 is a top plan view of the drier illustrating a portion thereof in section, showing the manner of connection of the arms with the cap plate;

Fig. 5 is a transverse sectional view;

Fig. 6 is a detail vertical section; and

Fig. 7 is a top plan view with a portion of the clothes supporting strands broken away.

Referring more particularly to the accompanying drawing, in which like characters of reference refer to corresponding parts in the several views, 5 designates an upright or tubular member supported in a plastic base 6, and mounted in said 45 up-right or tubular member 5 is an adjustable supporting member 7. This member 7 is likewise of a hollow tubular formation and provided with upper and lower closed end walls 8 and 9 respectively. The said adjustable supporting member may be ad-

justed at any suitable point by various arrangements, but I have shown and will describe the preferred form of such arrangement and that is preferably employed, embodying a base 10 consisting of a pair of 60 upper and lower inverted U-shaped frames 11 and 12 respectively. These arms are disposed within the upright or tubular member 5 and arranged in angular and superposed relation one to the other. The connecting portion 13 of each of said frames is formed with a bearing opening 14 serving as a bearing for the vertically disposed screw shaft 15. A shaft 16 is journaled in the limbs 17 of the support and carrying at on end, a 70 beveled gear 18, said gear being located between certain of the limbs of the frames and adapted to mesh with a pinion 19, said pinion being mounted on the lower end of the screw shaft 15. This screw shaft 15 has its 75 extreme lower end journaled in the connecting portion 13 of the lower frame 12 of the base and rotatably connected with such connecting portion through the medium of a bolt or nut 20. The upper end of said 80 shaft 15 is threadedly engaged in an opening 21 of the lower closed end wall 9 of the adjustable supporting member 7. One end of the shaft 16 is provided with a squared 85 end portion 22 and adapted to protrude through the opening 23 formed in the side wall, at a point adjacent the bottom edge thereof, of the stationary upright or tubular member 5. An operating crank 24 engages with the squared end 22 of the shaft 16 for imparting movement to the beveled gear 18 which in turn rotates the screw shaft 15, by its engagement with the pinion 19, as is clearly apparent from the drawing, and it will therefore be seen by such 90 operation the adjustment of the adjustable supporting member 7 within the upright or tubular member 5 will be effected.

The base 10, aside from being housed within the upright or tubular member 5, is 100 permanently connected therein by the engagement of the thumb nuts 25 with the threaded openings 26 formed in an annular band 27. These thumb nuts 25 are threadedly connected with the walls of the up-right 105 5 and arranged in a spaced concentric series. It is, of course, to be understood that the frictional contact of the adjustable supporting member 7 with the inner contour of the upright or tubular member 5 is suffi- 110

cient to prevent any accidental rotary movement of the supporting member 7 with respect to the upright or tubular member 5.

Detachably or otherwise suitably secured 5 on the stud 28 of the upper closed end wall 8, of the adjustable supporting member 7, by means of a thumb nut 29 is a cap plate 30. This cap plate 30 is in the form of an 10 annular disk and provided with pairs of diametrically oppositely arranged sockets 31. These sockets 31 are cast with the cap 30 and are of substantially triangular form in cross section, such sockets converging 15 from the marginal edge of the cap in a direction toward the axis thereof for receiving the supporting arms 32. Owing to the specific configuration of these sockets it will be apparent that the supporting elements 32 are snugly retained therein against any accidental lateral or rotary movement. The 20 arms 32 are illustrated as being of triangular form in cross section and conform to the contour of the sockets and frictionally engage with the walls thereof and further 25 assuring against the accidental displacement of the arms from said cap 30. Disposed in partial obstructing relation to the entrance 33 of the sockets and flush with the marginal edge of the cap 30, are upstanding 30 projections 33, the purpose of which is to firmly support the arms 32 at a slight elevated angle and prevent the sagging thereof when the arms are subjected to the weight of the clothes being dried. Furthermore, 35 these arms are each provided at spaced intervals throughout their length with a series

of line guides 34 for receiving the strands of clothes lines 35.

From the foregoing description, taken in connection with the accompanying drawing, the advantages of construction and of the method of operation will be readily apparent to those skilled in the art to which the invention relates, and while I have described the principles of operation of the invention, 40 together with the device which I now consider to be the best embodiment thereof, I desire to have it understood that the device shown is merely illustrative, and that such advantages may be made when desired as 45 are within the scope of the claims appended thereto.

I claim:

A clothes drier embodying an upright, a supporting member mounted therein, a screw shaft carried by said supporting member and having threaded connection at one end with the latter, an upper and lower U-shaped frame arranged in said upright, a transverse shaft journaled in the limbs of the upper frame, a beveled gear journaled 55 between the confronting ends of said frame, a pinion on said last mentioned shaft adapted to mesh with said beveled gear, and means for imparting movement to said shaft.

In testimony whereof I affix my signature in presence of two witnesses.

JOHN F. SCHEIDT.
